[57] **CLAIM**

The ornamental design for a parabolic slat antenna, as shown and described.

DESCRIPTION

FIG. 1 is a front perspective view showing our new design for a parabolic slat antenna according to the present invention;

FIG. 2 is a front plan view thereof;

FIG. 3 is a side elevational view thereof;

FIG. 4 is a side elevational view thereof opposite to that shown in FIG. 3;

FIG. 5 is a top plan view thereof;

FIG. 6 is a bottom plan view thereof;

FIG. 7 is a rear plan view thereof; and,

FIG. 8 shows the interfitting of slats according to our new design for the present invention.
